(57) **CLAIM**

The ornamental design for a combined side window and rear support for SUV soft top vehicle, as shown and described.

DESCRIPTION

FIG. 1 is a front, left perspective view of a combined side window and rear support for SUV soft top vehicle, shown in a position of use, and in accordance with the present invention;

FIG. 2 is a front, left perspective view thereof;

FIG. 3 is a front elevation view thereof;

FIG. 4 is a top plan view thereof;

FIG. 5 is a bottom plan view thereof;

FIG. 6 is a rear elevation view thereof;

FIG. 7 is a left side elevation view thereof; and,

FIG. 8 is a right side elevation view thereof.

The broken lines illustrating a vehicle in FIG. 1 depicts environmental structure that forms no part of the claimed design. The broken lines in FIGS. 2-8 shows portions of the combined side window and rear support for SUV soft top vehicle which form no part of the claimed design.
